US0D1020147S

(12) **United States Design Patent** (10) **Patent No.:** **US D1,020,147 S**
(45) **Date of Patent:** **** Mar. 26, 2024**

(54) **COMBINED VACUUM CLEANER AND HOLDER THEREFOR**

(71) Applicants: **JIANGSU MIDEA CLEANING APPLIANCES CO., LTD.**, Suzhou (CN); **MIDEA GROUP CO., LTD.**, Foshan (CN)

(72) Inventors: **Jin Wang**, Suzhou (CN); **Hyun Seon Shin**, Suzhou (CN); **Lu Wang**, Suzhou (CN); **Chang Liu**, Suzhou (CN); **Pei Cao**, Suzhou (CN); **Gang Liu**, Suzhou (CN); **Jian Xu**, Suzhou (CN)

(73) Assignees: **JIANGSU MIDEA CLEANING APPLIANCES CO., LTD.**, Suzhou (CN); **MIDEA GROUP CO., LTD.**, Foshan (CN)

(**) Term: **15 Years**

(21) Appl. No.: **29/781,236**

(22) Filed: **Apr. 28, 2021**

(30) **Foreign Application Priority Data**

Nov. 2, 2020 (CN) 202030657866.6

(51) **LOC (14) Cl.** **15-05**

(57) **CLAIM**

We claim the ornamental design for a combined vacuum cleaner and holder therefore, as shown and described.

DESCRIPTION

FIG. 1 is a front elevation view of a holder of the combined vacuum cleaner and holder therefor, showing our new design;

FIG. 2 is a back elevation view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view of thereof;

FIG. 8 is a front elevation view of a vacuum cleaner of the combined vacuum cleaner and holder therefor, showing our new design;

FIG. 9 is a back elevation view thereof;

FIG. 10 is a left side view thereof;

FIG. 11 is a right side view thereof;

FIG. 12 is a top plan view thereof;

FIG. 13 is a bottom plan view thereof;

FIG. 14 is a perspective view thereof;

(Continued)

FIG. 15 is a front elevation view of the combined vacuum cleaner and holder therefor, showing our new design;
 FIG. 16 is a back elevation view thereof;
 FIG. 17 is a left side view thereof;
 FIG. 18 is a right side view thereof;
 FIG. 19 is a top plan view thereof;
 FIG. 20 is a bottom plan view thereof; and,
 FIG. 21 is a perspective view thereof.
 The broken lines in the figures depict portions of the combined vacuum cleaner and holder therefor that form no part of the claimed design.
